UNITED STATES PATENT OFFICE.

JOSEPH F. WINKLER, OF PHILADELPHIA, PENNSYLVANIA.

REFRIGERATING SYSTEM.

Application filed January 17, 1922. Serial No. 529,840.

To all whom it may concern:

Be it known that I, JOSEPH F. WINKLER, a citizen of the United States, residing in Philadelphia, Pennsylvania, have invented
 5 **Refrigerating Systems**, of which the following is a specification.

This invention relates particularly to a novel arrangement of parts whereby the oil leaking past the piston or pistons of the
 10 compressor of a refrigerating system is automatically returned to the crank case of said compressor and one object of said invention is to provide novel means whereby such oil is collected in and caused to flow
 15 from the low pressure or evaporating side of the system.

It is further desired to provide a refrigerating system of the above type having such an arrangement of parts as to insure
 20 the return of the oil to the crank case in a cool condition, preferably under the action of gravity;—the invention especially contemplating a simple, compact, inexpensive and reliable arrangement of parts for attaining the desired end.

These objects and other advantageous ends I attain as hereinafter set forth, reference being had to the accompanying drawings, in which,

30 Fig. 1 is a diagrammatic elevation of a refrigerating system illustrating my invention as applied thereto; and

Fig. 2 is a diagrammatic elevation similar to Fig. 1, illustrating a modified form 35 of my invention.

In the above drawings 1 represents a compressor, in the case illustrated of the two-cylinder type, having its cranks set 180° apart and with the moving parts in the two
 40 portions of the crank case of substantially equal displacement. A condenser 2 is connected to the compressor by a pipe 3 and the refrigerant liquefied in said condenser is collected in a receiver 4. From this receiver a pipe 5 leads to any suitable automatically acting device 6 for feeding the oil which may leak past the pistons of the compressor, together with the liquefied refrigerant, to a refrigerant evaporator 7
 45 shown in the present instance diagrammatically as a tank, which by reason of the evaporation of the liquefied refrigerant within it is designed to cool a room or other surrounding space or objects. From the top
 50 of this tank 7 a pipe 8 leads to the intake of the compressor 1 and from a point ad-

jacent the bottom of said tank a second pipe 9 leads into the crank case of the compressor independently of the suction pipe 8.

Under conditions of operation, the crank case of the compressor is substantially filled with a suitable lubricating agent such as oil, glycerine, or the like and the tank 7 in addition to a body *x* of liquefied refrigerant, collects under the latter a body *y* of oil which has passed from the crank case of the compressor past the pistons, through the pipe 3, condenser 2, receiver 4, pipe 5 and feed controlling device 6. The gas compressed by the compressor 1 is liquefied in the condenser 2 and collected in the receiver 4 from whence it is forced into the tank 7. In the latter it evaporates and in gaseous form is drawn by the suction pipe 8 back to the compressor.

Since the crank case is normally maintained full of oil, any of it leaking past the working parts or pistons is at once automatically replaced by a like volume of lubricant flowing from the bottom of the tank 7 through the pipe 9 which opens into said tank a short distance above its bottom in order to prevent flow of dirt or material other than the lubricant, back to the compressor.

By the above arrangement of parts it is noted that the oil returned to the crank case is delivered from the cold or low pressure side of the system rather than from the high pressure side, so that the compressor itself is cooled by said oil as well as lubricated. This action is not only continuous but, as above described, is automatic.

In that form of my invention shown in Fig. 2, which is particularly adapted to a compressor 1^a having but a single cylinder and unbalanced moving parts in its crank case, the oil collecting in the lower part of the evaporating tank 7 flows through a separator 10 for dirt or other foreign material and from thence passes through a pipe 11 into a trap 12. The latter consists of a container connected through a pipe 13 with the interior of the crank case and also with a pressure equalizing pipe 14 to the upper part of said crank case. Within the container is a float 15 governing a valve 16 in such manner that the level of the liquid in the crank case is maintained substantially constant. In the event of the oil level falling, the float 15 falls and automatically admits oil through the valve 16 from the

lower part of the tank 7 until it has risen to the predetermined level, whereupon the consequent rising of the float in the container closes said valve 16 and temporarily prevents further flow.

As before, the flow of oil to the crank case occurs from the cold and low pressure side of the refrigerating system and is altogether automatic, tending to exert a cooling action 10 on the compressor and insuring that a predetermined amount of lubricant shall be present at all times in the crank case. Obviously the rise of lubricant in the crank case of the compressor cannot increase to 15 such a point as to interfere with the proper functioning of the piston.

I claim:

1. The combination in a refrigerating system of a compressor having a crank case; 20 a condenser connected to receive compressed gas from said compressor; a container outside and structurally independent of the compressor structure in which liquefied refrigerant is gasified; a conduit connecting 25 said container with the intake of the compressor; and a second conduit connecting the crank case of the compressor with the container in position to draw off therefrom by gravity and while the system is in operation the oil collecting therein.

2. The combination in a refrigerating system of a compressor; and means constructed to be operative while the system is in action for automatically returning to said 35 compressor oil collecting in the cool portion of said system comprising a conduit positioned to permit such return flow to occur under the action of gravity.

3. The combination in a refrigerating system of a compressor having a crank case; 40 a condenser connected to receive and liquefy gas from the compressor; a container in which refrigerant is gasified; conduits connecting said apparatus in a closed system; and a conduit connecting the lower part of the container with the crank case of the compressor in position to permit flow of oil 45 from the container to the crank case by gravity.

4. The combination in a refrigerating system of a compressor; a condenser connected to receive and liquefy gas from the compressor; a container in which refrigerant is gasified; conduits connecting said apparatus in a closed system; a conduit connecting the lower part of the container with the crank case of the compressor; the parts being positioned to cause flow by gravity through said conduit, and a device connected in said latter conduit for maintaining the 60 level of liquid in the crank case substantially constant.

5. The combination in a refrigerating system of a compressor; a condenser connected thereto for liquefying refrigerant; 65 a container; a device for feeding liquid refrigerant from the condenser to said container; a conduit connecting the upper portion of the container with the intake of the compressor; and a second conduit connecting the crank case of the compressor to the bottom portion of the container and positioned to automatically return by gravity and while the system is in operation lubricant collecting below the refrigerant.

JOSEPH F. WINKLER.
